UNITED STATES PATENT OFFICE

WILLIAM L. REID, OF LIMA, OHIO

LOCOMOTIVE-THROTTLE MECHANISM

Application filed June 18, 1925. Serial No. 37,905.

The object of the present invention is the provision of an improvement in throttle valve mechanism for locomotives which will ensure a better fitting valve and one which can be applied and machined with greater facility and the parts of which can be arranged in assembled position before mounting in place in the main throttle casting.

A further object of the invention is the provision in a device of the character specified of an arrangement which will permit the use of means that will ensure a more satisfactory machining of the interior bearings of the main throttle casting itself particularly the employment of a larger boring bar which will not spring and produce inaccurate results.

In order that my invention may be better understood, I will proceed to describe the same in connection with the accompanying drawings, in which

Fig. 1 is a sectional view of a throttle valve mechanism embodying my invention designed particularly for use in connection with the steam dome on the engine.

Fig. 2 is a side elevation of the device shown in Fig. 1.

Fig. 3 is a vertical section through another arrangement designed for use in the steam dome of the locomotive, the parts of the main throttle casting being somewhat altered from the form shown in Figs. 1 and 2.

Fig. 4 is a transverse sectional view on the line 4—4 of Fig. 3.

Referring now more particularly to Fig. 1 it will be seen that I have therein indicated a main throttle casting 1 having the outlet connection at 2 and an upper inturned flange at 3 which contains an opening through which there is placed a depending cage 4 that carries in its lower portion a cylindrical bearing 5 for receiving the balancing piston 6.

The lower end of the cage 4 is made with a stem 7 fitting into a bridge 8 formed integral with the main throttle casting 1.

Fitted within the opening at the top of the cage 4 is a seat ring 9 on which rests the valve 10 the diameter of the seat of which is

just a little smaller than the diameter of the piston 6. At the center of the valve 10 there is a pilot valve 11 carried by a stem 12 and cross bar 13 so as to be operated by the link 14 and a rocker lever 15 on the operating shaft 16. The stem 12 is so constructed that the pilot valve 11 has a slight movement relative to the valve 10, say approximately $\frac{1}{8}$ of an inch or a little over.

The cage 4 is arranged with an out-turned flange 17 which is apertured to receive a series of bolts 18 that fasten the cage down in position upon the main throttle casting 1, there being a tight joint between the bearing of the flange 17 and the upper surface 65 of the throttle casting 1 just surrounding the aperture within which the cage 4 rests.

In operation the pilot valve 11 is first opened which admits steam that surrounds the upper portion of the valve 10 downward through the central passage and around the stem 12 into the balancing chamber 6^a below the balancing piston 6, and the latter, being just slightly larger in diameter than the area of the seat of the valve 10, tends to exert an opening force on the valve 10 or if the pressures be substantially alike allows the action of the operating means through the connecting link 14 to raise the valve 10 to the desired extent permitting steam to flow past said valve and through the openings 19 in the cage 4 and out through the connection 2.

It will be observed from the above description that the piston 6 with the throttle 10 and the seat ring 9 and other cooperating parts are all kept in accurate and perfect alignment by having them all formed within the same casting, that is, the cage 4, and this casting, being easily removable from the main throttle casting 1, can be taken to a machine and bored or machined as required to get an accurate fit of all the parts, which is important in throttle valve devices, before the cage 4 is placed in its position in the casting 1. The only machining required to fit the cage 4 to the casting 1 is the aperture through which the cage 4 is entered and the slight plane bearing surface around such aperture just inside of the row of bolts 18.

In Figs. 3 and 4 I have shown a somewhat similar arrangement but modified slightly by eliminating the bridge 8 shown in Fig. 1 and substituting a number of shoes or faces 20 supported from the throttle casting 1, the cage 4 being of slightly altered construction at the bottom. It will be seen that in the construction shown in Figs. 1 to 4 inclusive the cage being relatively a small part can be machined with great accuracy and much more easily than handling the usual cumbersome and heavy throttle casting in its entirety. Besides this the parts of the throttle casting which do have to be machined are at the upper part of the same where they are easily reached by machine tools and, therefore, can also be readily machined with great accuracy especially as my improved design permits the use of a larger boring bar than the design in common use.

I claim:—

1. Throttle valve mechanism comprising in combination a valve casing having an opening therein and supporting means therebelow, and a removable cage slidable into engagement with said opening and said means and positioned thereby at its respective ends, together with movable valve parts all mounted in said cage, said parts comprising a main valve seating in the cage, a balancing piston in slidable relation to said cage and valve, and a stem carrying a pilot valve and the piston and being slidably mounted in the cage.
2. Locomotive throttle mechanism comprising, in combination, a throttle casing, having an opening therein and a guiding and supporting member inside the casing, a removable cage fitted into the opening having a socketed extension engaging said guiding and supporting member, a main valve, seating on said cage, having an aperture therein, a pilot valve associated with said aperture and having a stem extending therethrough, said stem slidably engaging said socket, and a balancing piston in the cage, mounted on said stem and slidably engaging said main valve.
3. Locomotive throttle mechanism comprising, in combination, a throttle casing, having an opening therein and a guiding and supporting member inside the casing, a removable cage fitted into the opening having a socketed extension engaging said guiding and supporting member, a main valve, seating on said cage, having an aperture therein, a pilot valve associated with said aperture and having a stem extending therethrough, said stem slidably engaging said socket, and a balancing piston in the cage, mounted on said stem and adapted, upon opening of the pilot valve, to bear against said main valve.

In testimony whereof, I have hereunto signed my name.

WM. L. REID.
